UNITED STATES PATENT OFFICE.

JOHN O. WOODSOME, OF NEW YORK, N. Y.

STEAM-CIRCULATING SYSTEM FOR DRIERS.

Application filed June 16, 1926. Serial No. 116,307.

This invention relates to a steam circulating system for driers and more particularly for paper machine driers.

In paper machine steam drier systems, one of the most important provisions necessary for efficient and economical use of the steam is the provision for rapid circulation of the steam through the drying cylinders without permitting appreciable loss through the escape of uncondensed steam. The use of low pressure steam and low back pressures on the driers also increases the economy of the system.

It is therefore an object of this invention to provide a steam circulating system for paper machine driers, wherein a rapid circulation of steam through the driers is effected by the use of Venturi type jet compressors and circulators and wherein loss through the escape from the driers of uncondensed steam is prevented by the use of nozzle separators.

It is a further important object of my invention to provide a steam circulating system for paper machine driers, wherein both high and low pressure steam may be used in connection with jet compressors of the Venturi type to effect rapid circulation and wherein means are provided for the reduction of the back pressure on the driers.

Other and further important objects of this invention will be apparent from the disclosures in the specification and the accompanying drawings.

This invention (in a preferred form) is illustrated in the drawings and hereinafter more fully described.

In the drawings:

Figure 1 is an end elevational view, with parts in section, of a steam drying installation for paper making machine driers.

Figure 2 is an end elevational view with parts in section, of a modified type of installation.

In the steam drying system illustrated by Figure 1 the reference numeral 1 indicates a steam drying cylinder of the usual type found on paper machines. Said cylinder 1 comprises a cylinder shell 2 and a head 3 at each end thereof, provided with journals 4 rotatably mounted in suitable bearings. The rear journal or trunnion, is commonly hollow to provide for the admission of steam to the drying cylinder 1. Steam is adapted to be admitted to the interior of the drier drum 1 through a passaged fitting 5 on said

extended trunnion 4. The removal of the condensate formed in the drier drum 1 is suitably accomplished by a curved siphon pipe 6 which extends from a point adjacent the lower portion of said cylinder 1 out through the extended trunnion 4 and separate therefrom to an end fitting 7. The removal of the condensate is of course effected by virtue of the steam pressure maintained within the drier drum 1, and is continuous throughout the drying operation.

Steam is supplied to the drying cylinder 1 preferably from two sources, a high pressure steam header 8 and a low pressure supply header 9. The low pressure steam ordinarily is obtained from the exhaust of steam engines and turbines used in other operations in the paper mill and the object is to use as much low pressure steam as possible in order to reduce the cost of steam for the drying operation. At the same time, it is necessary in order to obtain an efficient transfer of heat from the steam to the drying cylinder to provide a rapid circulation of the steam through the drying cylinder. In order to accomplish both of these ends I employ a jet compressor 10 in the inlet steam line 11 connecting the high pressure steam header 8 with the steam fitting 5 and join the low pressure header 9 to said jet compressor by means of piping 12. The purpose of the jet compressor is to effect a high velocity of steam with the use of small quantities of high pressure steam and further to create a suction for drawing into the inlet line low pressure steam at the required rate. The jet compressor 10 comprises an outer shell 13 flared outwardly and flanged at both ends and provided at its restricted intermediate portion with a slightly enlarged portion 50 having a side aperture 14 threaded to receive the pipe 12. An inner conical shell 15 is adapted to be fitted within one end of said outer shell 13 and is provided with a constricted orifice 16 at its reduced end which terminates adjacent the side aperture 14. A similar though preferably longer inner shell 17 is adapted to fit within the other end of said shell 13 and is provided with a relatively larger orifice 18 spaced apart a short distance from the orifice 16. The flared ends of said inner shells 15 and 17 are each provided with flanges 19 and 20 adapted to be received in corresponding recesses formed in the flat ends of the outer shell 13. The inner shells 15 and 17 are thus made readily

removable in order that shells having the required size of orifices 16 and 18 may be quickly installed to meet the demands of the particular drying system on which the jet compressor is to be used. Gaskets 21 may suitably be provided for each end of the shell 13 to form a tight joint between the flanged ends of said shell and flanged fittings 22 on the piping 11, said flanges being secured together as by the bolts 23.

A machine drain header 24 is connected to the steam fitting 7 by means of piping 25. In order to increase the velocity of the condensate removed through the piping 25, a restriction nozzle 26 is preferably installed therein. Said restriction nozzle 26 is somewhat similar in construction to the jet compressor 10 but is provided with only one inner shell 27 having a somewhat restricted orifice 28 and having no side aperture such as in the jet compressor.

In order to prevent the building up of a back pressure within the drain header 24 equal to or greater than the pressure in the supply header 9, an equalizing line 29 is provided joining said headers 9 and 24, and provided with a check valve 30 to prevent the flow of steam from the header 9 into the header 24. By this provision of an equalizing line, the back pressure on the driers can never exceed the pressure of the low pressure steam of the header 9.

It will be understood that in the practical application of my jet compressor to any particular drying system, the size of the orifice 16 must be very carefully calculated to deliver the required amount of steam to the driers 1 and to maintain the required differential of pressure between the inlet steam line 11 and the drain line 25 to insure rapid circulation of the steam.

The advantage of my jet compressor is that it effects the rapid circulation of the low pressure steam with the use of very small amounts of high pressure steam and without the necessity of employing pumps or other mechanisms having moving parts subject to wear.

In the form of installation illustrated in Figure 2, I provide in addition to a jet compressor 31 a Venturi circulator 32 connected in the inlet steam line 33 and a nozzle separator 34 connected in the drain line 35 and connected to the Venturi circulator 32.

The jet compressor 31 as before is connected in the inlet steam line 33 from the high pressure steam header 8 to the drying cylinder 1, and similarly the low pressure steam header 9 is connected by a pipe 36 to the side aperture 14 of said jet compressor 31. The Venturi circulator 32 which is preferably connected adjacent the jet compressor 31 is somewhat similar to said compressor except that its inner shells 37 and 38 are provided with relatively different sized

orifices 39 and 40 respectively. Said circulator 32 is also provided with a side aperture 41 adjacent the orifices 39 and 40 and threaded to receive a pipe 42 which connects said circulator to a side orifice 43 in the nozzle separator 34. Said nozzle separator 34 comprises an outer substantially cylindrical shell 44 flanged at each end and secured to flange fittings 45 by bolts 46 passing through said flanged ends. Only one inner shell 47 is provided in said separator 34, said shell 47 being conical shaped and having a restricted orifice 48 opening below the side aperture 43. Said side aperture 43 is positioned in a slightly enlarged central portion 49 of said separator 34. This construction permits the separation of the uncondensed steam from the condensate, since the condensate being delivered through the orifices 48 below the side aperture 43 tends to continue in its downward path through the pipe 35 into the drain header whereas the uncondensed steam is aspirated from the enlarged portion 49 through the piping 42 into the circulator 32. This aspiration of the uncondensed steam is due to the suction effect produced by the restricted orifice 39 in accordance with the well known Venturi principle. The result is a decided economy in steam, since little if any uncondensed steam is allowed to pass out into the drain header 24.

The operation of the installation just described is similar in as far as the jet compressor part is concerned to that already described in connection with the first installation. After the steam has passed through the jet compressor it passes through the reduced orifice 39, which increases its velocity and decreases its static pressure to the extent necessary to form a partial vacuum sufficient to draw the uncondensed steam from the separator 34 through the piping 42. The confined steam then passes through the upwardly flared inner shell 38 wherein the velocity is somewhat reduced, and through the piping 33 and the fitting 5 into the interior of the drying cylinder 1. The pressure of the steam within the drying cylinder 1 forces the condensate out through the siphon 6 and the steam fitting 7 into the drain line 35. In its passage through the separator 34 the uncondensed steam is separated from the condensate as described and the condensate passes on into the drain header and is removed from the system. It is obvious that the size of the various orifices must be carefully calculated to produce the required velocity of steam to the drier and the required drop in pressure between the separator 34 and the circulator 32. For instance, with a 5 pound pressure drop between points "A" and "B", the pressure at "A" being 6 pounds per square inch, a one inch throat corresponding to the ori-

ifice 39 will deliver 12 pounds of steam per minute to the drier. By calculations from suitable charts that may be prepared showing the flow of steam to the drier using various sized orifices, the correct size of orifice for any particular installation of driers may be readily computed. Since the inner shells of the various Venturi fittings are according to my construction interchangeable, it is a simple matter to change the capacities of the system in accordance with varying needs. It will be understood that while I have described my steam circulating apparatus in connection with drying systems for paper machines that said apparatus is equally applicable to other systems of drying mechanisms, as for instance in the drying of textile fabrics.

I am aware that many changes may be made, and numerous details of construction varied through a wide range without departing from the principles of this invention, and I therefore do not purpose limiting the patent granted hereon, otherwise than necessitated by the prior art.

I claim as my invention:

1. In a steam drying apparatus, a steam drier, a high pressure steam line, piping connecting said line to said drier, a jet compressor of the Venturi type in said piping, a low pressure steam supply header connected to said jet compressor at the constricted portion, a drain line from said drier, a Venturi fitting therein and a communicating conduit between said drain line and said steam supply header to equalize the back pressure in said drain line.

2. In a steam drying apparatus, a steam

drier, high and low pressure steam lines connected thereto, and a jet compressor in said connecting line for the purpose of drawing the low pressure steam into the drier.

3. In a paper drier system, a drier drum, high and low pressure steam lines, a jet compressor having a restricted orifice and a side opening adjacent said orifice, said compressor being connected to said high pressure line and to said drier drum, a conduit connecting said low pressure line to said side opening, a return drain line, and a restriction nozzle in said return drain line.

4. The combination with a paper machine drying cylinder, of a high and low pressure steam supply header, a steam inlet line connecting the high pressure header with the interior of the drying cylinder, a Venturi type jet compressor in said inlet line, and a pipe from said low pressure header to said compressor, whereby low pressure steam is drawn into said inlet pipe.

5. The combination with a paper machine drying cylinder of high and low pressure steam supply headers, a steam inlet line connecting the high pressure header with the interior of the drying cylinder, a Venturi type jet compressor in said line connected to said low pressure header, a drain header connected to the interior of said cylinder, and an equalizing line having a check valve therein between said drain header and said low pressure steam supply header for limiting the back pressure in said drain header.

In testimony whereof I have hereunto subscribed my name.

JOHN O. WOODSOME.
